UNITED STATES PATENT OFFICE

DWIGHT E. AUSTIN, OF LOS ANGELES, CALIFORNIA

DESIGN FOR AN AUTOMOBILE

Application filed November 20, 1929. Serial No. 33,501. Term of patent 14 years.

To all whom it may concern:

Be it known that I, DWIGHT E. AUSTIN, a citizen of the United States, residing at Los Angeles, in the county of Los Angeles and State of California, have invented a certain new, original, and ornamental Design for an Automobile, of which the following is a specification, reference being had to the accompanying drawing, forming a part thereof, in which Figure 1 is a perspective view of the automobile, with the view taken from one side and showing a portion of the forward end, and Figure 2 is another perspective view thereof taken from the same side but showing a portion of the rear end.

I claim:

The ornamental design for an automobile as shown.

In testimony whereof, I have hereunto set my hand at Los Angeles, California this 13th day of September, 1929.

DWIGHT E. AUSTIN.
